UNITED STATES PATENT OFFICE.

WILBUR F. JONES, OF BALTIMORE, MARYLAND, ASSIGNOR TO HOWARD CARLTON, OF SAME PLACE.

MOLDING-MACHINE.

SPECIFICATION forming part of Letters Patent No. 442,054, dated December 2, 1890.

Application filed October 11, 1890. Serial No. 367,824. (No model.)

To all whom it may concern:

Be it known that I, WILBUR F. JONES, a citizen of the United States, residing at Baltimore, in the State of Maryland, have invented 5 certain new and useful Improvements in Machines for Making Car-Axle-Box Cores, of which the following is a specification.

This invention relates to a machine for making the sand cores of molds used when 10 casting car-axle journal-boxes. Heretofore these cores were made of dry sand and were baked in an oven previous to placing them in the mold. Thus the sand could only be used once.

15 The object of this invention is to make the cores of what is commonly known as "green sand," which can be repeatedly used. The green-sand cores made by this machine are not baked, but are supported and held together by a carcass, which makes the core firm enough without baking.

20 In the accompanying drawings, illustrating this invention, Figure 1 is a front view of the machine. Fig. 2 is a side elevation and part 25 section of the machine, showing the case thereof lowered. Fig. 3 is a back view of the machine. Fig. 4 is a vertical cross-section of the upper portion of the machine, looking toward the front of the same. Fig. 5 is a vertical 30 longitudinal section of the machine, showing the case elevated. Fig. 6 is a vertical section and partial front view of the machine. Figs. 7, 8, and 9 show three views of the carcass which supports and gives strength to the core. 35 Figs. 10 and 11 are views of the top slides. Fig. 12 shows two views of the side slides. Fig. 13 is an edge view of one of the top bridges. Fig. 14 shows two views of one of the removable blocks.

40 The letter A designates the hollow frame or pedestal of the machine, which has near its bottom an outer shoulder a. From the lower shoulder a to the top the pedestal is round, like a cylinder, as at A'. The cylindric portion A' is hollow and at the top has an inturned flange b.

45 Resting upon the top of the cylinder A', and held in place by a tie-bolt b', is the bottom B of the case B', which forms the core-mold. This bottom B has an upward curve 50 at its front end, and projecting from this end

are lugs c, upon which rests the chill C, which produces a smooth facing on the metal casting at the lid-opening of the finished car-axle journal-box. In the present instance this 55 chill C also serves as the core-print which supports the front portion of the core-carcass in the sand mold while casting the metal. The one end of the tie-bolt b', previously referred to, enters the case-bottom B, and the other end 60 extends down the hollow cylinder A' and through a disk b², which takes against an inverted shoulder a' in the interior of the cylinder A'. The lower end of the bolt b' has a screw-thread upon which travels a tightening-nut b³. By this construction the case-bottom B is held in place on the top of the hollow cylindric pedestal.

65 A collar D, having at its upper end an outside flange d, encircles and is vertically movable on the cylindric pedestal A', and rests upon the outer shoulder a when lowered. (See Fig. 2.) The collar is provided with a spring-latch consisting of a bolt e, having a handle e' and a spiral spring e². The bolt 70 and spring occupy a socket e³ on the collar. When the encircling collar D is raised, the bolt enters a hole in the pedestal and thereby retains the said encircling collar at its raised 75 position. The sides and ends of the case B' are separate from the bottom B, and at the lower edge of each side is a flange f, which is fastened to the top flange d of the encircling collar D by bolts or any other suitable means. The case B' is open at the top, and the front 80 head E has its upper edge cut out or curved down, as at g, to allow for access to the chill C. It will now be seen that by the construction here described the case B' can be raised and lowered while the bottom remains stationary, for the reason that the one is entirely separate from the other. When the case B' is lowered and the encircling collar D is resting upon the shoulder a, the bottom 85 B, with the sand core, will be projecting above the case, as in Fig. 2. The bottom B extends back as far as a bridge h, which is on a higher plane and between it and the rear head E'. This bridge extends across the interior of the case B', from one side to 90 the other, and is fastened thereto. It forms a support for the back end of the core-car-

cess F, and also for the sand which forms the back core-print in the space *i*. The bridge *h* is raised and lowered with the case B', and when lowered the rear core-print is free, but is supported and prevented from falling to pieces by the carcass F, the object of thus freeing the said core-print being to facilitate the handling of the core by the operator.

10 The carcass F, previously referred to, is shown in detail in Figs. 7, 8, and 9, and gives strength to the sand core. It extends from the chill C at the front to the rear head E' of the case. This carcass F is hollow, and on

15 either side has projecting arms *j*, which support the sand that forms the core, and the front end *k* of the carcass passes through a hole in the chill C, and is held in position by pins *l*, which take between the wall of the 20 chill and lateral lugs *k'* on the projecting end *k* of the carcass. The chill-wall referred to (see Figs. 2 and 5) extends obliquely upward, so as to give the chilled face which is to form the front end of the journal-box a forward incline toward the bottom.

25 Vent-holes *m* extend through the walls into the hollow portion of the carcass and serve to carry off the gases generated by the heating of the core while pouring the molten metal.

30 The carcass F does not rest on the bottom B; but its front end *k* is supported by the chill C and its rear end *n* by the bridge *h* while ramming the core. The carcass, however, does extend along and very near the bottom

35 B. The said carcass has been shown and described as being hollow; but this hollow feature is not essential, as it could be made otherwise and yet employed as shown.

Near the center of the case B' and extending 40 downward from the top edge on either side of the interior of the said case is a removable block H, which makes provision in the core for the casting in the finished journal-box of the guides which hold the brasses 45 in which the journals of the car-axles revolve. The blocks H are the exact shape of the guides referred to, and can be removed from the case B' by drawing them upward by means of lateral lugs *o*, which project through notches *p* 50 in either side of the case B'.

Two slides I I' form in the core an imprint 55 for the casting of the slideway for the upper portion of the dust-guard at the rear of the finished journal-box. These slides extend down into the case B' to the center on either side and are cut out at the center to form a half-circle, so as to fit over the top portion of the car-axle. The metal in the finished casting which takes the place of the rear slide I' 60 forms the upper part of the back of the journal-box, and the space between this slide I' and the slide I is for the reception of a flat dry-sand core, which forms the slide-space in which the dust-guard will be placed. These 65 two slides I I' are removed from the case by drawing them out at the top.

Below the slide I and meeting it are two

slides K, which meet in the center of the case B'. Each side slide K forms a quarter-circle, and the two together form a half-circle at 70 their inner edges, and with the lower edge of the slide I form a complete circle. (See Fig. 6.) These slides K form the imprint in the core for the casting of the inner slideway of the dust-guard of the finished journal-box. 75 The side slides K enter the case B' through slots in the side walls, and by means of a projection K' can be removed by drawing them from either side of the case. Bolts L on either side of the case B' retain the slides K in position.

The object of making the blocks H, the slides I I', and the side slides K removable is to prevent them offering any obstruction to the lowering of the case B' when it is desired 85 to remove the sand core. The case is raised and lowered by a lever N, which is pivoted at *q* to an arm or standard P, extending upward from the base of the pedestal A. This lever has two arms, each being connected with the 90 flange *d* on the encircling collar D by means of a link *r*. To the other end of the two arms of the lever is attached a weight Q, which almost counterpoises the weight of the encircling collar D and the case B', and thus facilitates the work of the operator and makes it 95 easier for him to raise and lower the case.

It will be seen that by the construction here shown and the use of the carcass F a green-sand core can be made, which is much cheaper 100 than the dry-sand cores as formerly used.

Extending across the top and near the front of the case are two removable bridges S S'. One of these S' has on its under side a ridge *s*, which extends across the interior of the 105 case. This ridge *s* provides for the casting of the front stop for the front end of the journal-brasses in the journal-box. This bridge is held in place by two hooks *t*—one on either side of the case—which take over pins *u*, one 110 on either end of the bridge. This bridge S' also serves as the means for keeping the bridge S, which is between it and the chill C, in place.

It is evident that my arrangement could be varied in many slight ways which might suggest themselves to a mechanical mind. Hence 115 I do not limit myself to the precise construction herein shown, but consider myself entitled to all such slight variations as come within the spirit and scope of my invention. 120

Having described my invention, I claim—

1. In a machine for making the sand cores used in casting car-axle journal-boxes, the combination of a cylindric pedestal supporting the bottom of the core-case, a case having 125 sides and ends and separate from said bottom, a collar loosely encircling the said pedestal and vertically movable thereon and supporting the said case, and means to raise and lower the said collar and case.

2. In a machine for making the sand cores used in casting car-axle journal-boxes, the combination of a pedestal, the bottom of a core-case held in place on the pedestal, a case

having sides and ends to coact with said bottom, but separate therefrom, a chill for one end of the casting of the journal-box, a carcass having one end attached to said chill, 5 and means to raise and lower the case without disturbing the said bottom, the chill, or the carcass.

3. In a machine for making the sand cores used in casting car-axle journal-boxes, the 10 combination of a pedestal, the bottom of a core-case held in place on the pedestal, a case having sides and ends to coact with said bottom, but separate therefrom, a chill for one end of the casting of the journal-box, a bridge 15 ^h, fastened in the inside and extending across the rear end of the case, a carcass having one end attached to the said chill and the other to rest upon the said bridge, and means whereby to lower the case and bridge without disturbing the said bottom, the chill, or 20 the carcass.

4. In a machine for making the sand cores used in casting car-axle journal-boxes, the combination of a pedestal, the bottom of a 25 core-case held in place on the pedestal, a case having sides and ends to coact with said bottom, but separate therefrom, two removable top slides I I' and two removable side slides K in the case to provide for casting the dust- 30 guard slideway, and means whereby to lower the case without disturbing the said bottom.

5. In a machine for making the sand cores used in casting car-axle journal-boxes, the combination of a pedestal, the bottom of a

core-case held in place on the pedestal, a case 35 having sides and ends to coact with said bottom, but separate therefrom, two removable top slides I I' and two removable side slides K in the case to provide for casting the dust-guard slideway, a carcass for supporting and 40 giving strength to the core, and means whereby to lower the case without disturbing the said bottom or the carcass.

6. In a machine for making the sand cores used in casting car-axle journal-boxes, the 45 combination of a cylindric pedestal supporting the bottom of the core-case, a case having sides and ends and separate from said bottom, a collar loosely encircling the said pedestal and vertically movable thereon and supporting the said case, and a lever connected with the said collar and carrying a weight, as 50 and for the purpose set forth.

7. In a machine for making the sand cores used in casting car-axle journal-boxes, the 55 combination of a pedestal, the bottom of a core-case held in place on the pedestal, a case having sides and ends to coact with said bottom, but separate therefrom, a lever to raise and lower the case, and a spring-latch to 60 maintain the lever and case in position when raised.

In testimony whereof I affix my signature in the presence of two witnesses.
